UNITED STATES PATENT OFFICE.

JOHN GOOD, OF BROOKLYN, NEW YORK.

KEROSENE AND LIKE ENGINE.

1,359,166.

Specification of Letters Patent.

Patented Nov. 16, 1920.

Application filed April 9, 1918. Serial No. 227,489.

To all whom it may concern:

Be it known that I, JOHN Good, United States citizen, residing in Brooklyn, New York, have invented the following described

5 Improvements in Kerosene and like Engines.

My invention consists in an engine organization adapted for the more efficient combustion of liquid fuels of the heavier grades such as kerosene and more particularly in the temperature control of such engines as hereinafter more fully set forth, whereby the engine is adapted to burn such fuels with maximum efficiency and without the use of exhaust-heated vaporizers or other contrivances for preliminarily perfecting the charge.

Figure 1 is a diagrammatic representation of the automobile-type engine equipped with one form of the invention;

20 Fig. 2 a partial top plan thereof; and

Fig. 3 a diagrammatic side view representation of a modified form.

Referring to Fig. 1 the six cylinder engine shown may be assumed to be constructed for operation in the usual way, drawing its charge mixture of fuel and air from a carburetor 1 and having usual intake and exhaust valves in any suitable arrangement and such other appurtenances as may be necessary. The engine is air-cooled, that is to say is formed with numerous heat-radiating ribs or fins 2 on the walls of each of its cylinders and is contained in a hood or compartment 3 which is longitudinally divided by a horizontal partition 4 midway of the ends of the cylinders, so that air entering the space above the partition can find no outlet save through or past the said fins and thence into the lower compartment

40 thereby abstracting some of the heat from the engine. The flow of air in this direction may be produced in part by the forward motion of the automobile, if the engine is used for that purpose, or by the suction of a fan-type fly-wheel or preferably by both such agencies and all of which is in accordance with the well understood air cooling process. According to the present

invention the said air flow is controlled automatically or semi-automatically and with reference to the work the engine is doing and the nature of the fuel employed. In Fig. 1 it is controlled by the adjustable louvers 5 placed in the fan conduit 6 on its delivery or outlet side and under the control of the operator through a linkage system 7 which

system also controls the engine carburetor in such way that when the engine throttle is closed or partly closed the louvers are similarly and correspondingly closed. 60 Thereby the cooling air flowing past the cylinders is checked or stopped when the engine is throttled or adjusted to an idling or no load condition and the temperature of the cylinder walls is kept from falling as the 65 result of the reduced fuel combustion.

In Fig. 3 the air flow past the cylinder fins and out of the lower compartment is discharged upwardly by the fan-type fly-wheel 8 through a passage 9 containing a 70 balanced cylindrical valve 10, the interior of which is open to an outlet or escape for the air as indicated by the arrows. The movable valve member 10 is connected to a thermostat 11 of any suitable type, secured 75 in intimate heat-conducting contact with the engine cylinder casting of one of the cylinders preferably between the ribs thereon as indicated, and adapted to move the valve axially on changes of temperature of 80 the engine. The valve ports in this cylindrical valve are so arranged that a falling engine temperature communicated by conduction to the thermostat, will close them and restrict the outflow from the fan accordingly and thereby tend to restore the engine temperature by the reduced cooling effect. The particular form and mounting of the thermostat is not a matter of importance so long as the valve is operated in the 85 manner described and properly and sensitively responds to the temperature changes of the walls of the combustion space in the engine cylinders. The attachment of the thermostat to one cylinder suffices for all, 90 since they are presumed to be all operated under the same conditions, but the thermostat may be located at any other point which varies in temperature with the cylinder walls. In effect the thermostat function is 100 the same as that above described in that when the engine receives a minimum fuel supply, due to a reduction of load or speed, the tendency to cool is restrained resulting in a substantially constant engine temperature and in accordance with this invention that substantially constant cylinder temperature is maintained by the said automatic or semi-automatic control of the air flow at all times much higher than is possible in water-cooled engines and considerably higher than obtains in air-cooled en- 110

gines under normal conditions. The suitable degree has reference to the character of the fuel and with kerosene should be about 350° F. at the outside surface of the cylinder walls for best results. When the linkage is properly adjusted to maintain this condition the engine produces results in efficiency and practical convenience which cannot otherwise be obtained with heavy fuels without relatively great complication, if at all, and such an engine constitutes a practical solution of the problem of using kerosene for propelling automobiles and like purposes. Liquid fuel carried as spray or even as unsuspended liquid into the combustion spaces of this engine is burned therein with far greater efficiency than if the same fuel were first vaporized outside of the combustion space and subsequently introduced into it in an expanded condition as a mixture of vapor and air. High working efficiencies are thereby secured. The need for exhaust-heated vaporizers is entirely eliminated and the smell, expense and weight of such appliances are avoided. But especially the objectionable contamination of the lubricating oil in the crank case, by the escape of kerosene past the piston is completely eliminated because the above mentioned operating temperature is above that of the condensation of the liquid fuel and it is found that the liquid is vaporized and burned before it can pass the piston rings. In all types of engines receiving carbureted charge mixtures whether air-cooled or water-jacketed, thorough vaporization of the fuel liquid is especially sought and is most desirable to secure prior to its entrance to the cylinder, and various complicated vaporizer means have been devised to that end. In the present engine, on the contrary, the presence of fuel in its liquid form in the carbureted mixture is desired and serves the purpose of the invention by greatly increasing the volumetric efficiency of the engine and the power developed. On this account it is important, that careful provision be made that the several cylinders of the engine receive identical quantities of fuel in liquid form, whether suspended as spray or unsuspended in the form of a liquid stream entering the intake port with the air, and this invention therefore further includes the application of means for assuring equal distribution of the liquid to multi-cylinder air-cooled engines operating at the temperature above described, which as stated is always higher than water-jacket temperatures for all engine loads. In Figs. 1 and 2 such means are shown as consisting of a carburetor structure having a spray nozzle 12 opening into a mixing chamber to which air is admitted under the engine suction through a spring loaded air check 13 as usual in carburetors. Each intake valve port of the engine is connected to this chamber by a separate suction intake pipe 14 and the spray nozzle 12 is provided with plural spray orifices, one opening toward or into each intake, so that the air inrushing from the air check carries or sweeps equal amounts of liquid successively through each pipe to the corresponding cylinder. This method of distributing liquid-bearing charge mixtures is disclosed in a companion application filed March 16, 1918, Serial No. 222,828 and is preferred for the case in hand although it will be understood that other means may be used in its place to insure proper and equal admission of liquid to each cylinder.

Claims.

1. An internal combustion engine using kerosene or like heavy fuel, having its cylinder or cylinders provided with heat radiating projections and disposed in an engine-induced cooling air flow, in combination with supplemental means for varying said air flow adapted automatically to maintain the same or a higher cylinder temperature during no load as during full load, and means for supplying air and fuel in liquid form to said engine. 85
2. A multi-cylinder combustion engine using kerosene or like heavy fuel having its cylinders provided with heat-radiating projections disposed in an engine-induced cooling air flow, in combination with supplemental means for varying said air flow adapted automatically to maintain the same or a higher cylinder temperature during no load as during full load, and separate intake pipes for each of said cylinders connecting the same to a single carburetor whereby equal proportions of fuel liquid are delivered to each cylinder. 95
3. An internal combustion engine using kerosene or heavy fuel, having its cylinder or cylinders provided with heat radiating projections and disposed in an engine-induced cooling air flow, a throttle controlling said engine and means for varying said air flow in a predetermined relation to the position of said throttle. 100
4. An internal combustion engine having its cylinder or cylinders provided with heat radiating projections and disposed in an engine-induced cooling air flow, a throttle controlling said engine, means for varying said air flow and a connection between said throttle and means adapted to vary the temperature of the engine according to movement of the throttle. 110

In testimony whereof, I have signed this specification.

JOHN GOOD.
